UNITED STATES PATENT OFFICE

THOMAS HAVELOCK KINGSTON, OF WEST SOMERVILLE, MASSACHUSETTS, ASSIGNOR TO
BUILDERS' PATENT SCAFFOLDING COMPANY, A PARTNERSHIP COMPOSED OF
FRANK G. KINGSTON, A. R. KINGSTON, C. C. PIMM, AND MABEL G. KITCHEN, OF
WEST SOMERVILLE, MASSACHUSETTS

PUTLOG

Application filed March 5, 1929. Serial No. 344,504.

My invention relates to scaffolding or staging for workmen engaged in erecting brick and masonry walls and in particular to the horizontal supports known as putlogs which have devices at one end for detachable connection with the wall being erected, and at the other end rests upon horizontal supports that are secured to the vertical poles or directly to the poles. These putlogs consist of two parts 5 or members, one that includes a comparatively thin blade-like metal member that extends horizontally through a joint between adjacent bricks or stones and has a bearing upon the top of the under brick or stone, and the other 10 a bar made usually most readily and conveniently of wood. An acceptable putlog must combine the properties of efficient anchorage or bearing connection with the wall, facility of application to and removal from the wall 15 and that without damage to the latter on the front or exposed face, adequate strength because human life and limb are concerned, the minimum of cost, and such connection between the wall-engaging member and the 20 other member that they may be readily assembled for use even by unskilled labor so that the complete putlog need not be up at and sent out from the factory, but may be provided at some remote place from the factory 25 and thus cost of shipment or transportation be greatly reduced as by the shipment of the wall-engaging member alone. I have had in view all of the considerations just mentioned in producing my invention and in what I regard as its best and most satisfactory form 30 all of them are embodied therein, but it is to be understood that forms or embodiments of my invention may be employed in which less than all of the qualities or properties just mentioned will be found.

My invention consists in whatever is described by or is included within the terms or scope of the appended claims.

In the drawings:

Fig. 1 is a perspective view of a putlog embodying my invention;

Fig. 2 is a similar view of the wall-engaging or clincher member and the body separated from one another.

Describing briefly a putlog embodying my

invention, it includes the two essential parts of a comparatively thin bar which in use is thrust in the joint or space between adjacent bricks provided by omitting mortar between the bricks for the purpose, and the body member 55 which extends outward from the wall and constitutes the horizontal support for the planking that forms the platform for the workmen and which at the outer end rests upon or is supported by the horizontal ledger board. 60

Describing in detail what is shown in the drawings, the anchoring or wall-engaging member is a flat metal bar that is blade-like which has a bearing portion, 10, of sufficient length to extend between adjacent bricks of 65 a course, so that a downwardly extending hook, 11, at the free end may catch over the upper rear corner of the underlying brick and it has a shank, 12, which is an outward prolongation of the bearing member that 70 enters and extends a substantial distance into a metal tube or pipe, 13, which forms the putlog body and has a length to reach to the ledger board. At what may be considered the junction between the bearing member and 75 the shank there are on opposite sides of the blade two similar semi-circular discs, 14, that project at right angles and have a diameter small enough readily to enter the end of the pipe or tube and each half disc has 80 an outwardly projecting radial lug, 15, that enters and interlocks with a notch in the end of the pipe or tube to restrain or prevent rotation of the blade. Each half disc is integral with a wing, 16, that lies flatwise 85 against the side of the shank and a rivet, 17, passing through the wing and shank rigidly secures them together.

It will be seen that the body member of the putlog is simply a length of pipe or tubing 90 and is therefore inexpensive, is light in weight for ready handling and yet has ample strength to sustain the platform load resting upon it in use. And although the body and the wall-engaging or bearing member are detachably connected which is the 95 case to permit rapid and easy assemblage and taking down of the structure, yet when connected for use a strong rigid connection is afforded and adjacent the wall surface by the 100

multiplication of metal members thereat, the putlog has great resistance to shearing and bending stresses.

What I claim is:

- 5 1. A putlog comprising a tubular body and a wall-engaging member having a shank that extends into such body said wall-engaging member being flat and thin enough for insertion between adjacent bricks in a wall.
- 10 2. A putlog comprising a tubular body and a wall-engaging member having a shank that extends into such body, said member being blade-like and having lateral tube-engaging projections the tubular body having shoulders engaged by said projections.
- 15 3. A putlog comprising a tubular body and a wall-engaging member having a shank that extends into such body, said wall-engaging member being blade-like and having on opposite sides outwardly projecting tube-engaging lugs, the tubular body having shoulders engaged by said lugs and each of said lugs having a wing lying against the side of the portion of the member within the tube, and means securing the wings to such member.

In testimony whereof I hereunto affix my signature.

THOMAS HAVELOCK KINGSTON.
